UNITED STATES PATENT OFFICE.

NATHAN A. KURMAN, OF NEW YORK, N. Y., ASSIGNOR TO THE HERALD ELECTRIC COMPANY, OF NEW YORK, N. Y., A CORPORATION.

DESIGN FOR A LOUD SPEAKER.

Application filed December 18, 1926. Serial No. 20,061. Term of patent 3½ years.

To all whom it may concern:

Be it known that I, NATHAN A. KURMAN, a citizen of the United States, residing at New York city, in the county of New York and State of New York, have invented a new, original, and ornamental Design for Loud Speaker, of which the following is a specification, reference being had to the accompanying drawings, forming part thereof.

Figure 1 is a front elevation of my new speaker;

Figure 2 is a side elevation, and Figure 3 is a plan view of the base with the other parts omitted for the purpose of clearly showing the details thereof.

I claim:

The ornamental design for a loud speaker, as shown.

NATHAN A. KURMAN.
